UNITED STATES PATENT OFFICE

147,150

DESIGN FOR A CHAIR OR SIMILAR ARTICLE

William C. Roberts, Chattanooga, and Henry B. Powell, McMinnville, Tenn.

Application April 5, 1946, Serial No. 128,298

Term of patent 14 years

(Cl. D15—1)

To all whom it may concern:

Be it known that we, Henry B. Powell and William C. Roberts, both citizens of the United States, residing at McMinnville, in the county of Warren, State of Tennessee, and Chattanooga, county of Hamilton, State of Tennessee, respectively, have invented a new, original, and ornamental Design for a Chair or Similar Article, of which the following is a specification, reference being had to the accompanying drawing, forming part thereof.

The single drawing figure is a perspective view of a chair or similar article, showing our new design.

The characteristic features of our design reside in the portions shown by means of full lines in the drawing.

We claim:

The ornamental design for a chair or similar article, as shown and described.

WILLIAM C. ROBERTS.
HENRY B. POWELL.
